UNITED STATES PATENT OFFICE.

ANDREW HEIN, OF TRENTON, MISSOURI.

VEHICLE-WHEEL.

SPECIFICATION forming part of Letters Patent No. 247,911, dated October 4, 1881.

Application filed August 12, 1881. (Model.)

To all whom it may concern:

Be it known that I, ANDREW HEIN, of Trenton, in the county of Grundy and State of Missouri, have invented a new and Improved 5 Vehicle-Wheel, of which the following is a full, clear, and exact description.

The object of this invention is to facilitate the construction and easy running of vehicle-wheels.

10 The invention consists in providing the hub of the wheel with metallic bands having end cups adapted to contain boxes that carry rollers that bear on the inner circumference of the said cups or hub-band extensions.

15 In the accompanying drawings, Figure 1 is a longitudinal sectional elevation of my improved hub on line *x x*, Fig. 2. Fig. 2 is an end elevation of the same with cup removed. Fig. 3 is a cross-section on line *y y*, Fig. 1.

20 Similar letters of reference indicate corresponding parts.

In the drawings, A represents the hub-center, with spokes B radiating from it.

C represent the hub-bands, fitted upon the 25 hub A and conforming to the curves thereof, and held thereon by bolts *a a*, that are passed through their edges or flanges and through said hub-center A between the spokes B B. These bands C are provided with internal 30 annular shoulders, D D, extending at right angles to the faces of the bands C C, and fitting closely against the ends of the hub-center A, the openings in said shoulders being of sufficient diameter to permit the free movement of 35 the axle E. The ends of these hub-bands C are extended into cylindrical cups or sockets F F' for containing the boxes G G'. These boxes G G' are preferably made of cast metal, and have formed in their under surfaces, as shown

40 at *b b*, parallel and connecting grooves for the accommodation of the rolls H H. The front end of the axle E is of square cross-section, and the front box, G, is driven thereon, and held in place by screw *c*, that is screwed into 45 the axle end, as shown in Fig. 1. The axle E within the rear or inner cup or socket, F',

is round, and the inner box, G', is held thereon by a key or spline, *d*, as shown in Figs. 1 and 3. These boxes G G' have flanges *f f* formed at each end of the grooves *b b*, to afford supports for the screw-bolts I I, that are passed through them and the anti-friction rolls H H, and serve as axles for the latter to revolve upon. 50

The boxes G G' themselves being of somewhat less diameter than the cups or sockets F F', and the central bore of the hub A being of greater diameter than the axle E, the whole weight of the said axle E and the load supported by it must rest on the rolls H H, which run on the inner faces of the cups F F', so that 60 the vehicle-wheel will run more easily.

The open ends of the cups or band-sockets F F' are closed for keeping out dust and dirt by screw-caps K, fitted thereon, and held in place by screws *k* passed through their flanges 65 into the said sockets F F', and on removing these screws *k* oil for lubricating the parts may be introduced through the screw-holes.

Having thus described my invention, I claim as new and desire to secure by Letters Patent— 70

1. A vehicle-wheel constructed, substantially as herein shown and described, with hub-center A, bands C C, provided with internal annular shoulders, D D, cups F F', and boxes G G', carrying anti-friction rolls H H, arranged 75 as set forth.

2. In a vehicle-wheel, the combination, with the bands C, provided with the cups or sockets F F', of the boxes G G', provided with the flanges *f*, and the rollers H, journaled between 80 said flanges by the bolts I, substantially as and for the purpose set forth.

3. In a vehicle-wheel, the combination, with the hub-center A, of the bands C, secured to the said hub and provided with cups or sockets F F', formed by the interior shoulders, D, and end caps, K, substantially as and for the purpose set forth. 85

ANDREW HEIN.
